UNITED STATES PATENT OFFICE.

FREDERICK N. GARDNER AND FREDERIC E. GARDNER, OF BELOIT, WISCONSIN,
ASSIGNORS OF ONE-THIRD TO LOUIS WALDO THOMPSON, OF BELOIT, WISCONSIN;
ALICE M. GARDNER EXECUTRIX OF SAID FREDERICK N. GARDNER, DECEASED.

DISK GRINDER.

1,155,414.

Specification of Letters Patent.

Patented Oct. 5, 1915.

Application filed September 21, 1911. Serial No. 650,649.

To all whom it may concern:

Be it known that we, FREDERICK N. GARDNER and FREDERIC E. GARDNER, citizens of the United States, residing at Beloit, in the 5 county of Rock and State of Wisconsin, have invented certain new and useful Improvements in Disk Grinders, of which the following is a specification.

This invention relates to the particular 10 class of grinding machines known as disk grinders. Such machines comprise a rotatory wheel which is fixed on the extreme end of a spindle and is provided with a removable abrading surface on its unobstructed side or face opposite to the body of 15 said spindle. Heretofore the abrading surface has been formed by means of a disk of cloth or paper covered upon one side with a layer of abrasive grains, the other 20 side of said disk being cemented to the rotatory wheel of the grinding machine. In attaching the disk to the rotatory wheel it is necessary to use some kind of press for 25 pressing the disk closely and uniformly to the wheel. When the abrading surface is worn off, the disk and the cement must be removed from the wheel before another disk can be applied, such removal requiring the 30 use of hot water and scraping and scrubbing of the wheel with caustic detergents. The cloth or paper backing of the worn-out disk is discarded.

The necessity of cementing and pressing the disk to the wheel has seriously limited 35 the field of usefulness of disk grinders, because the press costs nearly as much as the grinder, the wheel must remain in the press for several hours, and the refaced wheel should be permitted to dry for two or three 40 hours after removal from the press, the grinder meanwhile being out of commission unless an extra supply of wheels has been provided.

The objects of our invention are to eliminate 45 the waste of material incident to the use of paper or cloth-backed disks, to save the expense of the cement, to reduce to a minimum the time, labor and investment involved in refacing the rotatory wheel, and to obtain greater grinding efficiency. These 50 objects we attain by providing a metallic wheel comprising two flat plate-like sections divided on a plane extending perpendicularly to the axis of the wheel or par-

allel to the side faces of said sections. One 55 section is rigidly fixed to the extreme end of the rotatory spindle of the machine, and the other section is approximately co-extensive with the first and comprises a thin disk or plate presenting a continuous or 60 unbroken forward side having a layer of abrading grains cemented directly to and covering said forward side, said wheel sections being detachably secured together face to face. 65

In the accompanying drawings, Figure 1 is a vertical central section through the rotatory wheel of a disk grinder embodying the features of our invention, a portion of the spindle being also shown. Fig. 2 is a 70 sectional view taken in the plane of dotted line 2 2 of Fig. 1, and upon a smaller scale.

In the drawing, 1 indicates the spindle and 2 the improved rotatory disk wheel, said wheel comprising a portion or plate 3 which 75 is attached to the spindle by means of the collar 4 and screws 5. Said wheel further comprises the thin disk or plate 6 provided upon one side with a layer of abrasive grains 7 cemented directly to said plate. 80 The wheel sections 3 and 6 are detachably secured together by any suitable means, preferably screw-threaded means to provide a clamping action, as for example, a plurality of cap screws 8. 85

When the abrasive coating 7 has been worn away the wheel is taken apart by removing the screws 8, the wheel-section 6 returned to the manufacturer to be refaced, and another section 6 having a new abrading 90 surface is secured to the wheel-section 3.

It will be apparent that our invention obviates the expense and annoyance of using cement to attach the abrading surface to the rotatory wheel, that the waste of material 95 incident to the use of cloth or paper-backed disks is obviated, and that a worn abrading surface may be expeditiously and conveniently replaced. Moreover, the abrasive grains, being cemented directly to metal, 100 have much more cutting efficiency than when mounted upon elastic and springy material such as cloth or paper, since when the abrading grains are attached directly to the metal they are positively and rigidly 105 held up to the material being ground.

We claim as our invention:

In a disk grinder, the combination of a

rotary spindle, a grinding wheel mounted thereon consisting of two flat plate-like sections divided on a plane extending perpendicularly to the axis of said spindle and 5 wheel, one of said sections being a circular metallic rear plate which is rigidly fixed on the extreme end of said spindle, the other section being a thin circular disk positioned face to face and co-extensive with said rear 10 plate, said disk having a layer of abrasive material cemented to and covering its unobstructed forward face, said face being plane and unrecessed and the disk and abra-

sive thereon presenting a continuous or unbroken flat abrading surface at all points 15 within its circumference, and a plurality of devices for clamping said disk to the face of said rear plate, said devices lying behind the plane of said layer of abrasive material.

In testimony whereof we affix our signatures in the presence of two witnesses. 20

FREDERICK N. GARDNER.
FREDERIC E. GARDNER.
